UNITED STATES PATENT OFFICE.

EVALD J. ENGMAN, OF SYRACUSE, NEW YORK, ASSIGNOR TO THE WILL & BAUMER COMPANY, OF SYRACUSE, NEW YORK, A CORPORATION OF NEW YORK.

MACHINE FOR FINISHING CANDLES.

1,114,871.

Specification of Letters Patent.

Patented Oct. 27, 1914.

Application filed March 17, 1914. Serial No. 825,193.

To all whom it may concern:

Be it known that I, EVALD J. ENGMAN, of Syracuse, in the county of Onondaga, in the State of New York, have invented new and useful Improvements in Machines for Finishing Candles, of which the following, taken in connection with the accompanying drawings, is a full, clear, and exact description.

10 This invention relates to certain improvements in machines for finishing candles after being molded to approximately the desired form and size.

The main object is to provide more expeditious and economical means for imparting to the candles a uniform size and smooth external finish in a single operation so as to increase the output with the expenditure of a minimum amount of time and labor.

20 Another object is to render the operation of drawing the candles through the dies as nearly automatic as possible, at least to the extent of locking the carriage for the candle supports in its extreme down position with the candle supports protruding through and below the dies to permit the wicks of the candles to be hooked there and also to regulate the speed and upward movement of the carriage in drawing the candles through 25 the dies and automatically stopping the upward movement of the carriage after the candles have been withdrawn from said dies.

A further object is to place the tripping of the locking device under the control of the operator so as to prevent the upward movement of the carriage from its extreme down position until the operator is ready for such movement or until the candles are properly attached to all of the candle supports.

40 A still further object is to counterbalance the weight of the carriage and elements carried thereby by means of a counterweight and pulley in which the counterweight acts as an initial starting device for the upward movement of the carriage to operate the clutch, whereby the pulley will be placed in connection with a continuously revolving shaft for completing the upward movement of the carriage.

45 Another object is to provide means for conveying any excess material which may be stripped from the candles away from the upper ends of the dies as the candles are drawn therethrough.

50 Other objects and uses relating to spe-

cific parts of the apparatus will be brought out in the following description.

In the drawings Figures 1 and 2 are respectively a front elevation and a side elevation of my improved candle-finishing machine showing the carriage in its extreme up-position and the clutch sections as disengaged. Fig. 3 is an enlarged longitudinal sectional view through the die-supporting cases and lower end of the carriage, said carriage being shown in its extreme down-position with the candle-supporting hooks protruding some distance below the dies for receiving the wicks of the candles. Fig. 4 is an enlarged transverse sectional view through the same die-supporting case. Fig. 5 is an enlarged horizontal sectional view through a portion of one side of the carriage and adjacent guide rod showing the locking device taken on line 5—5, Fig. 1, except that the carriage is in its extreme down position, showing the locking device in its locking position. Fig. 6 is an enlarged vertical sectional view of the same locking device in its locking position directly under the lower end of the clutch-operating rod, showing the lower adjacent portion of the carriage and guide rod therefor. Fig. 7 is an enlarged horizontal sectional view of the carriage-lifting mechanism taken on line 7—7, Fig. 1, showing also the underlying portions of the carriage and clutch-operating mechanism. Fig. 8 is an enlarged inverted plan of the clutch and means for throwing it into and out of operative position as shown in Figs. 1 and 7. Fig. 9 is a still further enlarged detail sectional view of the sliding clutch section and its operating means shown in Fig. 8 for forcing it into engagement with the die-clutch section on the main driving shaft. Fig. 10 is an enlarged detail sectional view, partly in elevation, of a portion of the clutch-operating means for disengaging the clutch sections.

The machine shown comprises a hollow base or casing —1— preferably rectangular in form and provided with an interior heating chamber —2— having an inlet —3— and an outlet —4— for the circulation of steam or other heating fluid therethrough, said casing being provided with a plurality of, in this instance twelve, vertical guide tubes —5— arranged side by side in sets or parallel rows of six each for receiving a

corresponding number of upright tubular guides —6— having upwardly tapering bores or circular passages —7— therethrough from end to end. These dies are 5 fitted in their respective tubular guides —5— so as to be removable for cleansing or repairs or for replacement and are provided at their opposite ends with annular shoulders —8— and —9— engaging respectively the top and bottom of the casing to hold them against relative endwise movement, the shoulders at the upper ends being preferably formed integral with the tubular dies while the lower shoulders —9— are 10 threaded and constitute nuts screwing upon the lower threaded ends of their respective dies by simply removing a corresponding nut —9—.

The tapering passages —7— through the 20 tubular dies —6— are preferably of the same size and form, but evidently may be made of different sizes if desired so that when the candles are drawn from the bottom upward through the passages, the upper ends thereof being heated by the heating fluid within the chamber —2—, will determine the diameter of the candles and also 25 impart a smooth finish to their surfaces.

The upper end faces or heads of the tubular dies are preferably beveled outwardly 30 and downwardly so as to cause any excess material which may be stripped from the candles during the operation of drawing them through the passages —7— to flow 35 away from said passages onto the outwardly and downwardly inclined upper faces —10— of the casing —1— and thence into longitudinally inclined channels —11— in the sides of the casing as shown more clearly in 40 Figs. 1, 4 and 5. The opposite ends of the casing —1— are provided with apertured lugs —12— in which are secured by pins —13— the lower ends of a pair of upright parallel guide rods —14— for partially supporting and guiding a vertically movable 45 frame or carriage —15— which is of light skeleton structure and is provided with lower and upper sets of apertured bearings —16— and —17— slidable along and upon 50 the rods —14—, those of each set being spaced some distance apart, one above the other, to prevent binding or cramping of the carriage on its ways.

Secured to the lower end of the carriage 55 is a plurality of, in this instance twelve, candle-supporting plungers —18— in vertical alinement with the axis of their corresponding tubular dies —6— through which they are adapted to pass as the carriage is 60 raised and lowered, the lower ends of said plungers being provided with hooks —19— adapted to protrude some distance below the lower ends of the tubular dies when the carriage is in its extreme down position to 65 permit the ends of the candle wicks to be

attached thereto so that the candles may be drawn upwardly through their respective dies when the carriage is elevated in a manner hereinafter described.

The carriage is preferably drawn downwardly by hand against the action of suitable retracting means as the counterweight —20— and for this purpose is provided with an operating arm or link —21— having its upper end pivoted at —22— to the 70 central portion of the carriage and its lower end provided with a handle —21'— within reaching distance of the operator standing up on the floor so that by pulling down upon the candle, corresponding movement 75 will be transmitted to the carriage.

The counterweight —20— is connected to one end of a cable —23— at the rear of the machine, said cable passing over a pulley or sprocket wheel —24— and having its other 80 end attached to an apertured lug on the central upper portion of said carriage as shown more clearly in Fig. 1.

Carriage locking means.—Suitable means is provided for locking the carriage in its 90 extreme down position to permit the candles to be attached to the lower ends of all of the plungers —18— thereon and for this purpose I have provided an upright rod —25— running parallel with and in close 95 proximity to one of the upright guide rods —14—, and also serving as a part of the means for shifting the clutch mechanism hereinafter described and, therefore, this rod —25— has a slight endwise movement. 100 The upper end of the rod is supported and guided in an apertured lug —26— of an overhead bracket —27— and is provided with a stop collar —28— for engaging the upper surface of the lug —26— and limiting the downward movement of the rod. The intermediate portion of the rod —25— is supported and guided in an apertured lug or bracket —29— on the adjacent side 105 of the upper portion of the carriage —15—, 110 said lug being provided with a transverse slot —30— for receiving a locking member —31— which is pivoted at —32— to the lug —29— to swing horizontally into and out of a position directly under the lower end 115 of the rod —25— when the carriage is moved to its extreme downward position as shown in Figs. 3 and 5.

The degree of movement of the carriage depends somewhat upon the length of the 120 candles operated upon, but must always be sufficient to project the lower ends of the plungers through and beyond the lower ends of the dies when the carriage is in its extreme downward position and to draw 125 the candles through and above the upper ends of the dies when in its extreme upward position and it, therefore, follows that the position of the lower end of the rod —25— depends upon the degree of movement of 130

the carriage and upon the length of the candles, but is always adjusted relatively to the locking member —31— so that the locking member will always ride under the lower 5 end of the rod —25— as soon as the hook-shaped extremities of the plungers —18— are brought a sufficient distance below the lower ends of the dies to permit the wicks of the candles to be hooked thereon prepara- 10 tory to drawing the candles through the dies by the upward movement of the carriage, said locking member being automatically forced to its locking position by a spring —33—, shown in Fig. 5, and is adapted to 15 be voluntarily tripped from its locking position at the will of the operator by means of a handle —34—.

Carriage lifting means.—After the wicks on the upper ends of the candles have been 20 attached to their respective hooks —19— on the plungers —18— on the carriage —15—, while the carriage is locked in its extreme downward position in the manner described, the locking member or catch —31— is 25 tripped from its locking position by hand, whereupon the counterweight —20— will start the carriage solely in its upward movement by reason of the fact that the counterweight is slightly heavier than the combined 30 weight of the carriage and candles mounted thereon, the object of which is to operate a suitable clutch presently described to connect a continuously rotating driving shaft to the sprocket wheel —24— for the purpose 35 of positively lifting the carriage to its extreme upward position. For this purpose, a driving shaft —35— is journaled in suitable bearings —36— on the overhead support —27— and is provided with a pulley 40 —37— adapted to be connected by a belt to any available source of power for driving the shaft continuously in the same direction indicated by arrow —X—, Fig. 1, said shaft being disposed in a horizontal 45 position some distance to the rear of the plane of the carriage so that the front side of the sprocket wheel will be disposed in such plane for direct connection with said carriage through the medium of the cable or 50 chain —23—. Secured to the shaft near one end is a clutch section —38— adapted to be engaged by a coaxial sliding clutch section —39— which is mounted upon the adjacent end of a sleeve —40— and is provided with 55 a cam face —41— to one end thereof for a purpose presently described. The sleeve —40— is loose on the main driving shaft —35— and is preferably journaled in suitable bearings —42— on the overhead support —27— at opposite sides of the hub of the wheel —24— which is secured to the sleeve by a set screw —43— as shown in Fig. 7, so that the bearings —42— hold the sleeve and sprocket wheel against relative 60 endwise movement. The clutch section 65

—39— is adapted to be moved into and out of engagement with the clutch section —38— by means of a shifting rod —44— which is slidable parallel with the shaft —35— in apertured lugs —45— on the front sides of 70 one of the bearings —36— and adjacent bearings —42— and is provided with a forked arm —46— adjustably secured thereto and engaged in an annular groove —47— on the clutch section —39— for shifting said 75 clutch section as the rod is moved in one direction or the other.

One of the lugs —45—, in which the clutch-shifting rod —44— is slidable, is provided with a hollow boss —48— in which is 80 mounted a spring-actuated plunger —49— having a tapered inner end for frictional engagement in sockets —50— in the adjacent side of the shifting rod —44— to frictionally hold said rod and clutch section actuated thereby in its shifted position and at the same time permitting those parts to be shifted by positive means presently described.

Shortly after the carriage has been started in its upward movement by the action of the counterweight —20— and after the locking member —31— has been released, the incidental rotation of the wheel —24— will cause a corresponding rotation of the sleeve 95 —40— and cam —41— mounted thereon, which cam will then ride against a roller —51— on one end of a rock arm —52— which is pivoted to the adjacent bearing —42— and yieldingly held in its operative 100 position by a light spring —43— against a shoulder —44— opposed to the direction of movement of the cam —41— so as to cause the shifting of the clutch section —39— into engagement with the clutch section —38—, thereby locking the sleeve —40— to the continuously rotating shaft —35— and causing the latter to drive the wheel —24— to continue the lifting of the carriage to its extreme up position or until 110 the clutch sections are automatically disengaged by mechanism presently described. This clutch-releasing mechanism consists of a collar —54— which is adjustably secured to the rod —25— and held in its adjusted 115 position by a set screw —56—, said collar projecting into the path of upward movement of the adjacent hub —17— on the carriage —15— so that as soon as the carriage reaches a sufficient height to entirely withdraw the candles from their respective dies, it will encounter the collar —54— and thereby raise the rod —25—. This rod —25— is provided with a transverse slot —58— for receiving one end of a bell-crank lever 120 —59—, the latter being fulcrumed or pivoted at —60— upon the adjacent bearing —36— and has its other arm disposed in a slot —61— in the adjacent end of the clutch-shifting rod —44— so that the elevation of 130

the rod —25—, as just previously described, operates the bell-crank lever —59— to shift the rod —44— and thereby disengage the clutch section —39— from the corresponding clutch section —38— to stop further upward movement of the carriage, whereupon the candles which have been drawn through the dies and thereby sized and finished may be detached from their respective hooks —19— and the operation previously described repeated. It may be stated, however, that as the carriage is drawn downwardly by hand, the wheel —24— and cam —41— will be rotated in a reverse direction from that required to move the carriage upward, thus bringing the high point of the cam —41— against the roller —51— which is free to rock in the same direction against the action of the retracting spring —43— until the point of the cam has passed the roller, whereupon the latter is immediately returned to its operative position ready to be engaged by said cam to force the clutch sections into operative engagement in the manner previously described.

What I claim is:

1. In a machine for finishing candles, a tubular finishing die, means for drawing a candle through the die comprising a reciprocating element and actuating means therefore including a clutch and means actuated by said element for releasing the clutch after the candle has been drawn through the die.
2. In a machine for finishing candles, a plurality of upright tubular dies, means for drawing candles through the dies comprising a vertically movable carriage having means for attaching candles thereto, a continuously rotating shaft, a clutch driven thereby, connections between the shaft and carriage, and means actuated by the carriage for releasing the clutch after the candles have been drawn through the dies.
3. In a machine for finishing candles, tubular finishing dies having passages therethrough tapering in the same direction, a carriage movable toward and from the dies and provided with means for attaching candles thereto for drawing them through the dies as the carriage is moved therefrom, means for moving the carriage away from the dies and additional means for automatically stopping the movement of the carriage from the dies after the candles have been withdrawn therefrom.
4. In a machine for finishing candles, a hollow casing having a heating chamber and an inlet for a heating fluid, a plurality of

upright dies passing through said chamber and provided with upwardly tapering passages therethrough, a vertically movable carriage having plungers movable through the passages and provided with means for attaching candles thereto for drawing said candles from the bottom upward through said passages, means for locking the carriage in its extreme down position to permit the candles to be attached to the plungers while the carriage is at rest, said locking means being voluntarily unlocked, automatic means for starting the carriage on its upward movement, a continuously rotating shaft, and means actuated by said starting means for connecting the starting means to the shaft for continuing the lifting movement of the carriage and thereby drawing the candles through said passages, and additional means actuated by the carriage for disconnecting the starting means from the driving shaft after the candles have been withdrawn from the dies.

5. In a machine for finishing candles, a tubular finishing die, a carriage movable toward and from the die, a plunger on the carriage movable through the die and provided with means for attaching a candle thereto, a continuously rotating driving shaft, a clutch section secured to the shaft, a sleeve loose on the shaft, a wheel secured to the sleeve, a clutch section feathered on the sleeve and movable into and out of engagement with the first-named clutch section, a cable on the wheel having one end connected to the carriage and its other end provided with a counter-weight to assist in raising the carriage, means including a catch for locking the carriage in its extreme down position, said catch being tripped voluntarily to permit the counter-weight to start the carriage in its upward movement and thereby actuate the wheel and sleeve, means actuated by such movement of the wheel and sleeve for throwing the sliding clutch section into engagement with the first-named clutch section to connect the shaft to the sleeve, and additional means actuated by the carriage for disengaging the clutch sections after the carriage has been moved upwardly a sufficient distance to withdraw the candles from the dies.

In witness whereof I have hereunto set my hand this 11th day of March, 1914.

EVALD J. ENGMAN.
